UNITED STATES PATENT OFFICE

116,131

DESIGN FOR A BURIAL CASKET

John Baker, Milton, Ind., assignor to The J. M. Doddridge & Sons Co., Milton, Ind., a corporation of Indiana

Application January 5, 1939, Serial No. 82,169

Term of patent 3½ years

To all whom it may concern:

Be it known that I, John Baker, a citizen of the United States, residing in the town of Milton, in the county of Wayne and State of Indiana, have invented a new, original, and ornamental Design for a Burial Casket, of which the following is a specification, reference being had to the accompanying drawing, forming a part thereof,

in which Figure 1 is a perspective view of the casket, showing my new design, Figures 2, 3, and 4 being a top plan view, a side elevation, and an end elevation, respectively, of the casket.

I claim:

The ornamental design for a burial casket, substantially as shown.

JOHN BAKER.
